UNITED STATES PATENT OFFICE.

THOMAS McCABE, OF YORKVILLE, OHIO.

PLATE-LIFTING MECHANISM FOR HOT MILLS.

1,418,815.

Specification of Letters Patent. Patented June 6, 1922.

Original application filed June 17, 1919, Serial No. 304,825. Divided and this application filed September 4, 1920. Serial No. 408,258.

To all whom it may concern:

Be it known that I, THOMAS McCABE, a citizen of the United States, residing at Yorkville, Ohio, have invented a certain 5 new and useful Improvement in Plate-Lifting Mechanism for Hot Mills, of which the following is a full, clear, and exact description, such as will enable others skilled in the art to which it appertains to make and use 10 the same.

This application is a division of my pending application for patent on plate lifting mechanism for rolling mills, Serial No. 304,825, filed June 17, 1919.

15 The main object of my present invention is to provide a practicable plate lifting mechanism for hot mills that embodies the good features and characteristics of the plate lifting mechanism described in my 20 pending application for patent previously referred to, namely, it overcomes the necessity of employing two catchers stationed at the rear of the rolls of the mill to receive the plates as they are discharged from the 25 rolls and manually raise the plates into such a position that they can be grasped and pulled forwardly over the top roll of the mill by the operator stationed at the front of the mill, and it handles hot plates more 30 rapidly and efficiently than is possible when workmen are employed for this purpose.

Another object is to provide an inexpensive and rigid plate lifting mechanism for hot mills that will not be affected by the 35 heat from the hot plates or the scale that drops off the plates.

And still another object is to provide a plate lifting mechanism for hot mills which comprises a receiving table for the finished 40 plates that can be tilted by the operator stationed at the front of the mill, to discharge a plate therefrom.

Figure 1 of the drawings is a side elevational view of a plate lifting mechanism 45 constructed in accordance with my invention, showing the plate lifter carriers in their raised position.

Figure 2 is a perspective view of one of the plate lifter carriers.

50 Figure 3 is a detail top plan view, illustrating the clutch and other co-operating parts of the controlling mechanism used to govern the operation of the plate lifter carriers; and

55 Figure 4 is a side elevational view of the

receiving table arranged at the rear of the rolls of the mill.

In general design and principle of operation, the plate lifting mechanism herein illustrated is substantially the same as the 60 plate lifting mechanism described in my pending application previously referred to, except that the cycle of the plate lifters is merely from their depressed position to their elevated position, or from their elevated position to their depressed position, 65 the plate lifters coming to rest at the end of the cycle and remaining at rest either in their elevated position or in their depressed position until the operator in charge of the 70 machine actuates the device that causes the plate lifting mechanism to start operating. The plate lifters are rigidly connected to the vertically reciprocating carriers instead of being hinged to said carriers, as in the 75 mechanism described in my pending application previously referred to, and are preferably provided with guides so as to prevent a plate from moving off the receiving table at the rear of the mill in the event said 80 plate is discharged crookedly from the rolls of the mill.

Referring to the drawings which illustrate the preferred form of my invention, A and B designate the top and bottom rolls of a hot 85 mill, C designates a receiving table arranged at the rear of the rolls A and B so as to receive the plates as they are discharged from the rolls of the mill, and D designates one of a pair of plate lifters that is connected to a vertically reciprocating carrier E arranged at the rear of the rolls A and B of the mill. The mechanism comprises two vertically reciprocating carriers E arranged longitudinally of the table C at opposite 90 sides of same, as in the mechanism shown in my pending application previously referred to, but only one of said carriers and its cooperating plate lifter is herein shown, on account of the fact that most of the parts 95 of the mechanism herein illustrated are identical with the corresponding parts of the mechanism described in said application, the principal difference between the two mechanisms consisting in rigidly connecting each 100 plate lifter D to its co-operating carrier E, as herein shown, instead of hinging said plate lifter on its carrier; in the omission in the mechanism herein illustrated of the means for swinging the plate lifters rel- 110

atively to their carriers and in constructing the controlling apparatus of the mechanism herein illustrated in such a manner that the operator in charge of the mill will have to 5 actuate a controlling device whenever he desires to have the plate lifters moved either upwardly or downwardly.

Normally, the carriers E are arranged in such a position that the plate lifters D on 10 said carriers will be positioned at opposite sides of the receiving table C in approximately horizontal alignment with the top side of said table. When a plate is passed through the rolls of the mill it is discharged 15 from said rolls onto the table C. Thereafter, the operator stationed at the front of the mill actuates a controlling device which causes the carriers E to move upwardly into the position shown in Figure 1 of the drawings, 20 thereby causing the plate to be lifted from the table C and moved upwardly into such a position that the operator can grasp the front end of said plate and pull it forwardly over the top roll of the mill. Before feeding another plate through the mill the operator actuates a controlling device so as to cause the carriers E to move downwardly 25 into their depressed position.

Each of the carriers E is supported at its 30 front end by a link 2 and at its rear end by a link 3 of slightly greater length than the link 2, the link 2 having its upper end pinned to a shaft 2^a and the link 3 having its upper end pinned to a shaft 3^a. Each of said links 35 consists of a relatively wide device, as shown in Figure 2, provided with two spaced side portions whose ends are connected together by cross pieces or hubs so as to impart sufficient rigidity and strength to said links to 40 eliminate the possibility of the carrier tilting sidewise with relation to said links. The shafts 2^a and 3^a are journaled in bearings on a supporting structure F, and means is provided for turning said shafts so as to swing 45 the links 2 and 3 upwardly and downwardly, and thus raise and lower the carrier E supported by said links. The means for rocking the shafts 2^a and 3^a consists of an oscillating member G carried by the supporting 50 structure F and provided at its upper end with two racks 5 and 6 that mesh with gears 5^a and 6^a on the shafts 2^a and 3^a, respectively. When the actuating member G rocks forwardly, or to the right, looking at Figure 55 1 of the drawings, the shafts 2^a and 3^a will turn in a direction to lower the carrier E with which said actuating member G is associated. When said actuating member rocks in the opposite direction, said carrier E will 60 move upwardly into the position shown in Figure 1. In order to assist the actuating member G to lower and raise the carrier E, the shafts 2^a and 3^a are provided with counterweights 2^b and 3^b, respectively. The 65 plate lifter carrier (not shown) that is ar-

ranged at the opposite side of the table C is operated by an actuating member, similar to the member G, which is rigidly connected to the member G by a cross shaft 4, as shown in Figure 1, that is journaled in the two supporting structures F arranged at opposite sides of the table C and having the operating shafts 2^a and 3^a of the plate lifter carriers journaled therein. The mechanism for actuating the two members G of the 70 mechanism is not herein illustrated in detail, as it is of the same construction as the corresponding part of the mechanism described in my pending application previously referred to and consists of cams on a transversely-disposed shaft 8 which engage and move the members G when the cam shaft 8 is in operation, one of said cams being shown in dotted lines in Figure 1 and designated by the reference character 8^a. 75

The cam shaft 8 is rotated by a sprocket chain 9 which passes around a sprocket wheel 9^a on said cam shaft and around a sprocket wheel 9^b on the operating shaft H, said sprocket wheels being so proportioned that the gear ratio between the shaft H and the cam shaft 8 will be two to one, or, in other words, of such proportion that the cam shaft 8 will make one-half a revolution at each complete revolution of the shaft H. 80

When the plate lifter carriers E are in their depressed position they lie in a substantially horizontal plane, but when said carriers are in their elevated position, the front ends of same tilt downwardly slightly, 95 as shown in Figure 1, so as to hold the plate on the plate lifters D in such a position that the operator can easily draw said plate forwardly off the plate lifters. This slight upward tilt of the carriers E is obtained by 100 making the links 3 slightly longer than the links 2 and connecting the upper ends of the links 3 to the carriers by sliding bearings or blocks x arranged in elongated slots y in the carriers, as shown in Figure 2, the upper ends of the links 2 being pivotally connected to the front ends of the carriers. The carriers E at opposite sides of the receiving table C are connected together by a cross bar or rod (not shown) so that they will move 105 in unison, and each of the plate lifters D on said carriers is preferably provided with a guide 104 so as to prevent a plate from moving off the receiving table C in the event said plate is discharged crookedly from the 110 rolls of the mill, as sometimes occurs. The operation of the plate lifter carriers E is governed by a clutch under the control of the operator stationed at the front of the mill. As shown in Figure 1, the mechanism 115 comprises a transversely-disposed shaft 30 that can be driven from any suitable source of power, said shaft being provided at one end with a gear 32 that meshes with a gear 120 loosely mounted on the shaft H and ar- 125 130

ranged directly underneath the gear 32. A clutch member 34 is keyed to the shaft H, as shown in Figure 3, and a co-operating clutch member 34^a is secured to the loose gear which meshes with the gear 32 on the shaft 30, the clutch member 34 being acted upon by a spring 35 that exerts pressure on same in a direction tending to move it into engagement with the clutch member 34. A horizontally-disposed shaft 41 that is journaled in bearings on the frame of the mill is provided with an upwardly-projecting arm 42 whose upper end is bifurcated and arranged in engagement with a locking plunger 43, as shown in Figure 3, that normally holds the clutch member 34 out of engagement with the clutch member 34^a, the clutch member 34 being provided with a cam 134 with which the inner end of the locking plunger 43 operates. When the clutch members 34 and 34^a are in engagement with each other the shaft H will rotate with the constantly operating shaft 30, and thus impart movement to the cam shaft 8 which actuates the members G. To start the plate lifting mechanism the operator pulls downwardly on the hand lever 45 that is connected to the shaft 41 or depresses a foot pedal 46 that is connected by means of a link 47 with the hand lever 45, thereby causing the arm 42 on the shaft 41 to retract the locking plunger 43 or move it out of engagement with the cam 134 on the clutch member 34. As soon as said clutch member is released from the locking plunger 43 the spring 35 moves said member into engagement with the clutch member 34, thereby causing the shaft H to start to rotate, the end of said plunger 43 thereafter being held in yielding engagement with the hub of the cam 134 on the clutch member 34 by any suitable means, such, for example, as a spring 46^a connected to the foot treadle 46. When the shaft H makes one complete revolution and the cam shaft 8 makes one-half of a revolution the spring-actuated locking plunger 43 will pass from the hub of the cam 134 into engagement with the inclined face of the cam 134 and render the clutch member 34 inoperative, thus causing the shaft H to come to rest. It will thus be seen that it is necessary for the operator to trip the locking plunger 43 each time he desires to have the plate lifters move either upwardly or downwardly.

The receiving table C at the rear of the rolls of the mill is constructed in such a manner that the front end of same can be tilted upwardly by a mechanism under control of the operator at the front of the mill, so as to discharge a hot plate from the table after the rolling operation has been completed. As shown in Figure 4 of the drawings, the table C is pivotally mounted on a supporting structure in such a manner that the front end of said table can be tilted

upwardly, as indicated in broken lines in Figure 4, by depressing an operating device 106 at the front end of the mill which is connected by means of a link 107 to a rock arm 108 secured to the table C. When the pressure is removed from the operating device 106 the table is returned to its normal horizontal position by means of a spring 106^a connected to some part of the table 75 tilting mechanism, or the table can be pivotally mounted on the supporting structure in such a way that gravity will restore the table to its horizontal position as soon as the pressure is removed from the operating device. 80

A plate lifting mechanism of the character above described embodies the essential characteristics and features of the plate lifting mechanism described in my pending application for patent previously referred to, but it will not be affected by the heat from the hot plates or the scale that drops off the plates. Moreover, it can be made very strong and rigid and it can be built at a low cost on account of its simple design. 90

Having thus described my invention, what I claim as new and desire to secure by Letters Patent, is:

1. A plate lifting mechanism for hot mills, comprising a support arranged at the rear 95 of the rolls of the mill to receive the plate discharged from the rolls, vertically-movable carriers arranged at opposite sides of said support and adapted to move relatively to said support, rigid or immovable plate 100 lifters on said carriers, and means comprising a counterweighted mechanism and a source of power that drives said mechanism for bodily raising said carriers so as to cause the plate lifters on the carriers to engage a plate 105 that has been discharged from the rolls of the mill and bodily lift or raise said plate into such a position that the operator can grasp the plate and pull it forwardly over the top roll of the mill, said means also operating to lower said carriers. 110

2. A plate lifting mechanism, comprising a vertically-reciprocating carrier provided with a plate lifter, supporting links for said carrier, and a bearing on one of said links 115 slidably mounted in elongated slots in said carrier.

3. A plate lifting mechanism, comprising a vertically-movable carrier, rock shafts 120 journaled in a supporting structure and provided with devices that are pivotally connected to said carrier, one of said devices having a bearing that is slidably mounted in an elongated opening in said carrier, counterweights secured to said rock shafts, 125 a drive shaft, and mechanism arranged between said drive shaft and rock shafts for turning said rock shafts positively in opposite directions so as to raise and lower said carrier. 130

4. A plate lifting mechanism for rolling machines, comprising a table arranged to receive the plates that are discharged from the rolls of the machine, means separate and distinct from said table for moving the plates upwardly into a position to be engaged by the operator stationed at the front of the

machine, and a manually-operable means adapted to be actuated by the operator in charge of the machine for tilting the table 10 so as to discharge a plate therefrom at the completion of the rolling operation.

THOMAS McCABE.
